UNITED STATES PATENT OFFICE.

GEORGE L. NEWTON, OF HAVERHILL, MASSACHUSETTS.

MACHINE FOR BURNISHING THE HEELS OF BOOTS AND SHOES.

SPECIFICATION forming part of Letters Patent No. 229,168, dated June 22, 1880.

Application filed March 31, 1880. (Model.)

To all whom it may concern:

Be it known that I, GEORGE L. NEWTON, of Haverhill, in the county of Essex and State of Massachusetts, have invented an Improvement in Machines for Burnishing the Heels of Boots and Shoes; and I do hereby declare that the following is a full and exact description thereof, reference being had to the accompanying drawings, making part of this specification.

My improvement is upon that part of a heel burnishing or polishing machine termed the "jack," or by which the boot or shoe is clamped in the machine and held in position while subjecting the edges of the heel-lifts to the action of the burnishing tool or part of the machine. It is especially applicable to the Tapley heel-burnishing machine, and machines of that class in which the burnisher travels around the heel and is pressed with the force of a strong spring against the same, as exemplified in Letters Patent Nos. 113,658 and 169,884; but it may be applied to any machine wherein the boot or shoe is held by a clamp pressed against the inside of the boot or shoe opposite to the heel. Heretofore the head or face of the clamp, which presses against the inside of the boot or shoe and holds it upon the heel-seat of the jack, has been that of a simple fixed head attached to the end of a sliding spindle or bar without adjustment thereon; and as it has to be used with boots and shoes of many different sizes and having heels of various shapes, it does not afford sufficient support of the heels and back part of the boots and shoes against the powerful pressure of the burnishing tool, since it does not fit closely back in the shoe or boot to hold that part firmly in position.

My improvement consists in a clamp head or form having a shape approximating to that of the interior of a boot or shoe next to the back, and not too large to enter all sizes to be placed thereon for burnishing, the said head or form having a lateral self-adjusting movement on its spindle or holder, and arranged to yield in position and spring close into the back part of the boot or shoe, so as to hold it very firmly in position, and also having a self-adjusting movement around the axis of its

spindle or holder, to adapt itself to the required position of the boot or shoe in the heel-seat of the machine.

Referring to the accompanying drawings, Figure 1 represents a side view of the clamp 55 spindle or holder of a heel-burnishing machine and my improved adjustable clamp-head mounted thereon; Fig. 2, a central longitudinal vertical section thereof; Fig. 3, a back view of the clamp head or form, the back part 60 of the spindle or holder being removed; Fig. 4, a section of the same in a plane indicated by the line xx , Fig. 1.

Like letters designate corresponding parts in all of the figures.

In the drawings, A represents the sliding spindle or holder to which heretofore the clamp-head has been rigidly attached.

By my improvement I apply a collar or swiveling part, B, to the end of the spindle or holder, the end of the spindle fitting therein, as at a , so as to allow the collar to turn or swivel thereon, and the two parts are or may be held together by means of a peripheral groove, b , in the tenon of the spindle, into which enters 75 the inner end of a screw or coupling-pin, c , inserted into one side of the collar; or the extension part B may enter the bored or tubular end of the spindle as an equivalent of the construction above described.

Upon the end of the collar or swiveling part B is a head or enlargement, d , which fits in an interior oblong socket or way, f , in the clamp head or form C, so as to allow the latter to have a vertical sliding movement on the spindle or holder, and yet be retained firmly in its upright position thereon, the arrangement of the spindle in the kind of machines referred to above being horizontal. A neck, g , with parallel sides on the collar B, slides also in a narrow 85 way or slot, h , in the back of the head or form continuous with the socket f , and thus the form C has a free vertical adjusting movement while being held securely on the spindle.

As an efficient and convenient means of introducing the head d of the spindle or of its collar into the socket f of the clamp-form, I make the said form in two parts, i l , each containing a part of the socket f and slot h , the two parts being united by screws m m , or their 90 100

equivalent. The forms of the two parts as I have made them are indicated by their lines of connection y y and z z , Fig. 3. The lateral or vertical movement of the clamp-form on the spindle allows it to adapt itself in position so as to fit close back in each boot or shoe, of whatever size or of whatever shape or position of the heel thereon, so that it will fit the heel-seat of the machine also, the turning or swiveling movement of the form on the spindle completing its capability of self-adjustment in the boot or shoe when the latter is in position. Thus the boot or shoe is held firmly to the burnishing-tool, and is not liable to break down, bend over, or the heel-lifts to crack apart. In order to make this adjusting movement of the clamp head or form automatic and complete, I apply a spring, D, thereto in such a manner as to push the form with some force up into the back of the boot or shoe when clamping it in the machine. As represented, it is simply a flat spring, secured at one end to the spindle-collar B, at n , some distance from the form, while the free end bears against the upper wall of the neck-slot h in the form, as shown. The swiveling collar B on the spindle allows this arrangement of the spring without interfering with the free turning of the form on its axis; but a coiled or other form of the spring D might be employed, to be located in the form

itself and bear against the spindle direct or against a washer-collar on the spindle, the spindle-head being round, so as to turn in its socket f , and its neck round, so as to turn in its slot h ; but I prefer the construction substantially as represented in the drawings.

What I claim as my invention, and desire to secure by Letters Patent, is—

1. In a boot and shoe heel burnishing machine, a laterally-movable clamp or form, C, in combination with the jack-spindle A, substantially as and for the purpose herein specified.

2. The combination of the laterally-movable clamp head or form C, jack-spindle A, and spring D, substantially as and for the purpose herein specified.

3. The combination of the jack-spindle A, turning collar B, and laterally-movable clamp head or form C, substantially as and for the purpose herein specified.

4. The socketed clamp head or form C, formed in two parts, i l , in combination with the collar B, having the head d , substantially as and for the purpose herein specified.

The foregoing specification signed by me this 18th day of March, 1880.

GEORGE L. NEWTON.
